UNITED STATES PATENT OFFICE

HENRY TRICE MITCHELL, OF KANSAS CITY, MISSOURI, ASSIGNOR TO THEODORE G. JOHNSON, OF KANSAS CITY, MISSOURI

FIRE ALARM

Application filed December 19, 1925. Serial No. 76,502.

My invention relates to fire alarms and my object is to provide a simple, reliable and inexpensive apparatus of this character which can be installed at small cost in private dwellings, hotels, factories, etc.

A further object is to provide a novel switch for controlling the circuits of the alarm apparatus, and in order that the invention may be readily understood reference 10 will now be had to the accompanying drawing, in which:

Fig. 1 is a side elevation of the apparatus constituting the invention with the parts in normal position in full lines and in dotted 15 position after having transmitted an alarm.

Fig. 2 is a front elevation of the apparatus in the position it occupies after transmitting an alarm.

Fig. 3 is a longitudinal section of a container employed in carrying out the invention.

Referring in detail to the different parts, 1 designates a metallic or other fire resistant holder of semitubular form connected at 25 one end by a pivot 13 to the lower end of a suitable support such as a bracket 2 which is adapted to be secured to a ceiling or other support with screws 12. The opposite end of the holder 1 is provided with a hook 16 for engagement with one end of an alloy or 30 other fuse 3, the opposite end of which is adapted to engage over a hook 16 depending from the upper portion of the bracket 2 as shown by Fig. 1.

35 4 designates a container consisting of glass or other suitable nonconducting material and secured in the holder 1 by metallic straps 6. The container 4 is provided with a quantity 40 of conducting material, consisting preferably of mercury, which is free to travel from one end of said container to the other.

7 designates a pair of contacts extending 45 through the end of the container 4 nearest the pivoted end 13 of the holder 1. Said contacts 7, together with the mercury 5, constitute a part of a normally closed circuit including binding posts 9 and circuit wires 10 and 15. The binding posts 9 are supported 50 by but insulated from the bracket 2 and have

the respective circuit wires 10 and 15 connected thereto as shown by Figs. 1 and 2.

The end of the container 4 nearest the fuse 3 has a pair of contacts 8 extending therethrough and forming a portion of a normally 55 open circuit including a pair of binding posts 9^a, circuit wires 11 and circuit wires 17. The binding posts 9^a are supported by but insulated from the bracket 2.

In practice the holder 1 is suspended in an 60 inclined position by the fuse 3 as shown by Fig. 1. This causes the mercury 5 to flow to the lower end of said container 4 and uncover the inner ends of the contacts 8 and submerge the inner ends of the contacts 7, thereby 65 opening the circuit through the wires 11, binding posts 9^a and the wires 17, and closing the circuit through the wires 10, the binding posts 9 and the wires 15.

Should a fire occur in the vicinity of the apparatus 70 and cause the temperature to rise sufficiently to destroy the fuse 3, the holder 1 and the container 4 will immediately swing downwardly to the dotted line position Fig. 1, whereupon the mercury 5 will uncover the 75 inner ends of the contacts 7 and submerge the inner ends of the contacts 8, thereby closing the signal circuit through the wires 11, the binding posts 9^a and the wires 17, and open the circuit through the wires 10, the binding posts 9 and the wires 15.

After the fire has been extinguished the apparatus may be reset by swinging the holder 1 upwardly to its former position and supporting its raised end with a new fuse 85 engaged over the hook 17.

From the foregoing description it is apparent that I have provided an apparatus embodying the advantages above pointed out, and while I have shown and described one 90 form of the invention I reserve all rights to such changes and modifications as properly fall within the spirit and scope of the invention as claimed.

I claim:

In a fire alarm, a thermal switch consisting of a rightangular support, a semitubular holder pivotally connected at one end to the lower end of said support, a hook at the opposite end of said holder, a hook on the upper 100

portion of the support, a fusible link connected to said hooks for supporting the holder in an upwardly inclined position, a container carried by and having its lower portion inclosed in said holder and provided with a liquid conductor, contacts projecting into one end of the container which are covered by said conductor when the holder is held in upwardly inclined position, and contacts projecting into the opposite end of said container which are engaged by the conductor when the holder swings downwardly on destruction of the fusible link.

HENRY TRICE MITCHELL.
